(57) CLAIM

The ornamental design for a compact rechargeable sweeper, as shown and described.

DESCRIPTION

FIG. 1 is a front perspective view of a compact rechargeable sweeper which embodies our design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof; and,

FIG. 7 is a bottom plan view thereof.

The material in dotted lines forms no part of my design.
